A. V. RYDER, OF NEW YORK, N. Y.

Letters Patent No. 99,484, dated February 1, 1870.

IMPROVED HASP FOR TRUNK-LOCKS.

The Schedule referred to in these Letters Patent and making part of the same.

To all whom it may concern:

Be it known that I, A. V. RYDER, of the city, county, and State of New York, have invented a new and useful Improvement in Trunk-Locks, of which the following is a full, clear, and exact description, reference being had to the accompanying drawing, forming part of this specification, and in which—

Figure 1 represents a front view of a trunk-lock, as applied to the locking-portion of a trunk;

Figure 2, an inside view of the hasp of the lock, as attached to the lid or opening-portion of the trunk;

Figure 3, a section through the lid and body or lock-portion of the trunk, together with the lock-case and hasp, showing the latter as closed, or shut to its place in the lock.

Similar letters of reference indicate corresponding parts.

Owing to the rough usage which trunks for traveling-purposes are exposed, it is a matter of no small importance, to guard against any injury to the lock, as, for instance, by the sliding of one trunk over the other, or in various other ways.

The only or most exposed portion of the lock is the hasp, which, as it is usually fitted, forms a projection, not only at its hinge or joint, but also generally across or over it, from the face-plate of the lock.

My invention has for its object the remedying of this defect, and

It consists in forming the face-plate of the lock or trunk-surface, down or against which the hinged hasp fits when closed, with an indentation or recess in it, to receive within said face-surface, the main or body-portion of the hasp.

Also, the invention includes an inside arrangement of the hinge or joint to the hasp, and indentation or recess, made in the face-plate of the lock or trunk-surface, for such hinged portion to lie in when the hasp is closed.

In this way, or by these means, the hasp is pro-

tected from being strained or torn off, in or during the handling of the trunk, by reason of the flush or embedded character given it, relatively to the outside surface of the trunk, when closed and locked.

Referring to the accompanying drawing—

A represents the lid or opening-portion of the trunk, to which the stationary portion *a* of the hasp *B* is nailed, under cover of a band, *b*, or otherwise.

The movable or locking-portion *c* of said hasp is represented as hinged to the stationary part *a*, by a joint, *d*, so arranged as to form an inside projection on the hasp, the main or body-portion of which latter, when closed, is made to lie within an indentation or recess, *e*, formed in the face-plate *C* of the lock, or outside surface of the trunk-body *D*, while the joint *d* fits or enters another or deeper recess, *f*, therein.

By these means or provisions, both the plate and joint-portions of the hasp are prevented from protruding and being caught or struck, to the detriment or wrenching off of the hasp, in or during any rough handling of the trunk, or sliding of another trunk or body over it.

What is here claimed, and desired to be secured by Letters Patent, is—

1. A trunk-lock, in which the hasp *B*, when closed, is made to lie within a recess, *e*, formed in the face-plate of the lock or outside surface of the trunk, substantially as specified.

2. The hasp *B*, formed with its joint *d* on the back or inside face of it, in combination with the recess *f* in the face-plate of the lock or outside surface of the trunk, essentially as shown and described.

3. The combination of the hasp *B*, having its joint *d* arranged as described, of the recesses *e* and *f* in the face-plate of the lock, or outside-surface of the trunk, substantially as specified.

A. V. RYDER.
